FIG. 1

Managing SUDS in West Virginia

Jane Jameson

Updated May 28 at 4:55pm

**Counties in West Virginia need attention
for substance abuse**

SUDS diagnosis rates by county are high in the following counties.

FIG. 2A

FIG. 2B

Member Costs

We are spending \$1.29 billion dollars in 2021 managing SUDS patients in West Virginia. Acute hospitalization costs related to drug abuse have been rising steadily for years.

SUDS Patient Member Costs

Updated October 12, at 8:48pm | From: 2021 SUDS Member Costs by County

\$7,249

Average PMPY for members with SUDS compared to \$3,206

179,000

Members with SUDS in West Virginia

\$5,297

Avg. One Day Acute hospitalization cost

\$1.29 B

Total estimated cost for members with substance abuse disorder for 2021

SUDS Diagnosis Rates By County

Updated October 12, at 8:48pm | From: 2021 SUDS Member Costs by County

*** Cabell County *** Wayne County *** Harrison County

FIG. 2C

Recommendations

1. Target members in these counties with Health Insurance.
2. Move over-prescribing physicians out of network to drive patients to the right providers.

1. Target members with Health Insurance
